Specification for Design.

Patented June 8, 1920.

Application filed September 18, 1919. Serial No. 324,701. Term of patent 7 years.

To all whom it may concern:

Be it known that we, DOUGLAS H. ELEY and THOMAS H. RYAN, citizens of the United States, residing at Norfolk, in the county of Norfolk and State of Virginia, have invented a new, original, and ornamental Design for Rubber-Shoe Plates, of which the following is a specification, reference being had to the accompanying drawing, forming part thereof.

The figures are respectively a plan view of and a longitudinal section through a rubber shoe plate, showing our new design.

We claim:—

The ornamental design for a rubber shoe plate, as shown.

DOUGLAS H. ELEY.
THOMAS H. RYAN.
